CLAIM

The ornamental design for a testing device, as shown and described.

DESCRIPTION

FIG. 1 is a top perspective view of a testing device with its cap on;

FIG. 2 is a top view of the testing device with its cap on;
FIG. 3 is a bottom view of the testing device with its cap on;
FIG. 4 is a left side view of the testing device with its cap on;

FIG. 5 is a right side view of the testing device with its cap on;

FIG. 6 is a front view of the testing device with its cap on;
FIG. 7 is a rear view of the testing device with its cap on;
FIG. 8 is a top perspective view of the testing device with its cap off;

FIG. 9 is a top view of the testing device with its cap off;
FIG. 10 is a bottom view of the testing device with its cap off;

FIG. 11 is a left side view of the testing device with its cap off;

FIG. 12 is a right side view of the testing device with its cap off;

FIG. 13 is a front view of the testing device with its cap off; and,

FIG. 14 is a rear view of the testing device with its cap off. The broken lines in the figures depict portions of the testing device that form no part of the claimed design.

1 Claim, 14 Drawing Sheets
